UNITED STATES PATENT OFFICE.

EDWARD H. FINDLAY, OF FAIRFIELD, IOWA.

FLASH LIGHT.

Application filed April 17, 1923. Serial No. 632,649.

To all whom it may concern:

Be it known that I, EDWARD H. FINDLAY, a citizen of the United States, residing at Fairfield, in the county of Jefferson and State of Iowa, have invented certain new and useful Improvements in Flash Lights, of which the following is a specification.

In carrying out the present invention, it is my purpose to provide a flashlight, where-
10 in the body portion of the same is provided with a generator of relatively small dimensions, together with means for operating the generator, whereby electricity will be generated for the usual electric lamp of the flash
15 light, thereby doing away with the necessity of providing the usual dry cell batteries, which must needs be changed from time to time.

A further purpose of this invention is the
20 provision of a flash light, wherein the main body portion thereof is provided with a generator, as well as an operating means there-
of, of comparatively simple construction, and of such a nature as to embrace the de-
25 sired features of efficiency and durability.

The nature and advantages of the invention will be better understood when the following detailed description is read in connection with the accompanying drawings,
30 the invention residing in the construction, combination and arrangement of parts as claimed.

In the drawings forming part of this application, like numerals of reference indicate
35 similar parts in the several views, and wherein:—

Figure 1 is a side elevational view of a flashlight constructed in accordance with the present invention.

40 Figure 2 is a detail longitudinal cross sectional view thereof.

Figure 3 is an end elevational view.

Figures 4, 5, 6 and 7 are detail cross sections, taken substantially upon the lines
45 4—4, 5—5, 6—6, 7—7, respectively, of Figure 1, and

Figure 8 is a perspective of the actuating member for the clutch comprised in this invention.

50 Referring to the drawings in detail, 5 designates a cylindrical casing, upon the front end of which is secured a reflector 6 of conventional type, which carries the usual lens 7. Within the front end of the said cas-
55 ing 5 and extending through an opening therein, as well as an opening within said

reflector is a lamp bulb socket designated generally by the numeral 8, and within which is the usual electric lamp 9. Within the casing 5, and adjacent the front end thereof is a generator 10, which is of relatively smaller dimensions, and embodies the usual shell 11, armature 12, and shaft 13. This generator is secured within the casing by set screws or other appropriate fastening means 14. Rearwardly of the generator 5 is a flanged disk or plate 15, secured within the casing 5 by set screws 16, it being of course obvious that this plate or disk is provided with a central opening for permitting of a passage of the armature shaft 13 there-
60 through. Pivoted at 17 to this disk or plate, and at a point beneath the armature shaft 13 is a pair of arms 18, the same extending upwardly, and engaging through an opening in said casing 5. Each of these arms 18 is formed with a notch 19, adjacent the armature shaft 13, and it will of course be obvious that when these arms are forced in a direction towards each other, a braking action will be occasioned upon the said armature shaft, for consequently stopping rotation thereof.

As a means for actuating the said arms 18, the side edges of the opening within the casing 5 are formed with guide flanges 19, the upper ends thereof being provided with inwardly extending fingers 20. Slidable between these guide flanges and beneath the said fingers 20 is a plate 21 of slightly arcuate shape, and formed upon its bottom face with a relatively wide channel 22, the side edges of which converge inwardly towards the end of the plate for obviously effecting a movement of the arms 18 towards each other, when the said plate is moved forwardly. Forwardly of this plate 21, the casing 5 is provided with an abutment 23, for limiting the sliding movement of the plate in this direction.

Extending partially within the opposite end of the casing 5 is a spring barrel 24, the end of the barrel within the casing being open, and having engagement with a disk or plate 25, that is secured as at 26 within the casing 5. The plate or disk 25 is formed with a central opening, within which is the open end of a relatively elongated thimble 27, which extends rearwardly within the barrel 24, the length of the same being sub-
100 stantially equivalent to the length of the barrel.

Extending longitudinally within the thimble 27 is the reduced end 28 of the armature shaft, loose upon which is a spur gear 29, this gear being rigidly connected to the 5 said thimble 27. The opposite end of this shaft extends through a central opening in the end wall of the barrel 24, and is equipped with a speed governor 30.

Within the barrel 24 is a band spring 31, 10 one end thereof being riveted or otherwise rigidly secured to the said thimble 27, while the opposite end is secured in a like manner to the barrel 24. Upon the end wall of the barrel 24 is a ratchet plate 32, the peripheral 15 edge of which provides ratchet teeth 33, Figure 6. Rigidly connected to the end of the casing 5 is a sleeve or collar 34, the end of the same adjacent the ratchet disk being formed with inwardly bent spring fingers 20 35, which engage the said teeth 33 of the ratchet disk for preventing the unwinding of the spring.

Freely rotatable upon the end of the casing 5, within which is the spring barrel 24 25 is the reduced end of a collar 34 attached to the end of the casing 5, it being noted that between the adjacent ends of the collars 34 and 36, respectively, there is positioned a skirt portion of an end cap 37. The collar 30 36 is secured to the said end portion of the skirt cap through the medium of set screws or the like 38 while the spring barrel 24, ratchet disk 32, and end cap 37 are rigidly secured together by bolt connections 39. 35 Between the flanged disk 15 that is secured at 16 within said casing 5, and the end plate 25 of the spring barrel 24 is a plate or disk 40, that is also secured within the casing, through the medium of set screws, or other 40 appropriate fastening means.

This member 40 is provided with a central opening, through which extends a reduced end of the armature shaft 13, there being keyed upon this shaft forwardly of the gear 45 29 a small spur gear 41. This gear is intermeshed with a pair of relatively larger gears

42, upon opposite sides thereof, the same being journaled between the disk 40 and plate 25 of the spring barrel 24. Each of these gears 42 have formed upon one face 50 thereof a relatively smaller gear 43, in mesh with the gear 29 upon the end of the shaft 28.

In view of the above description, it will at once be apparent that when the arms 18 55 are contracted upon the armature shaft 13, the spring 31 may be wound by a rotation of the collar 36 and cap 37. By sliding the plate 21 forwardly, the armature shaft will be released, which will permit the unwinding of the spring 31, for consequently 60 rotating the thimble 27 within the plate or disk 25, for consequently effecting a rotation of the armature through the several gears, thereby generating current for the 65 electric lamp 9.

Although I have herein shown and described the preferred embodiment of the present invention, it is nevertheless to be understood that minor changes may be made 70 therein, without departing from the spirit and scope of the invention as claimed.

Having thus described my invention, what I claim as new, and desire to secure by Letters-Patent is:

A flashlight comprising a casing, an electric generator located therein, a spring motor housed within the casing, transmission means connected with the shafts of the motor and the generator, an automatic governor carried by the shaft of the motor, brake arms pivotally mounted within the casing and disposed transversely of the shaft of the generator and positioned one at each side of the shaft of the generator and having 80 end portions extending through the side of the casing, and a plate slidably mounted upon the casing and having a channel with converging walls which receive the ends of the arms between them. 90

In testimony whereof I affix my signature,
EDWARD H. FINDLAY.
